UNITED STATES PATENT OFFICE.

HAROLD W. EDEN, OF CHICAGO, ILLINOIS, ASSIGNOR TO BROKAW-EDEN MANUFACTURING COMPANY, A CORPORATION OF MISSOURI.

DRIVING MEANS.

1,241,100.

Specification of Letters Patent. Patented Sept. 25, 1917.

Application filed January 26, 1914. Serial No. 814,411.

To all whom it may concern:

Be it known that I, HAROLD W. EDEN, a citizen of the United States, and a resident of the city of Chicago, in the county of Cook and State of Illinois, have invented certain new and useful Improvements in Driving Means; and I do hereby declare that the following is a full, clear, and exact description of the same, reference being had 10 to the accompanying drawings, and to the numerals of reference marked thereon, which form a part of this specification.

As heretofore constructed devices involving the use of a number of shafts and gears 15 have been more or less difficult of assembly due to the necessity of properly alining the same and truing up the various elements in order to obviate friction and wear on the parts, and to insure easy running and operation of the same. This invention relates 20 to means permitting rapid assembly without accurate alinement of elements forming a portion of a drive for a washing machine, although it is obvious that the adaptation 25 thereto is not necessarily limited to this particular type of construction.

It is an object of this invention to construct a reversible driving mechanism for a washing machine or the like wherein the 30 various shafts are detachably connected together to permit operation thereof even if the same are not properly alined, thus obviating friction, wear, and binding of the parts.

It is also an object of this invention to construct a device wherein the elements are easily and quickly assembled, and wherein any part thereof may be removed, without interference with, or adjustment of other 40 portions of the device.

It is also an object of this invention to construct a reversible driving gear mechanism wherein the various shafts and gears may be readily removed from the device by 45 the removal of connecting pins which removably but positively engage the same together, thus requiring no interference with other portions of the device.

It is furthermore an object of this invention to construct a device wherein the elements are loosely but positively engaged together by means of pins, thus permitting a slight play between the elements, requiring no accurate alinement of the same in assem-

bly, and also permitting rapid and easy assembly thereof.

It is finally an object of this invention to construct a device involving the use of elements detachably pinned to one another, permitting the removal of any one element 60 therefrom without interference with other elements of the device.

The invention (in a preferred form) is hereinafter more fully described and defined in the accompanying drawings and 65 specification.

In the drawings:

Figure 1 is a side elevation of a washing machine to which a particular form of this type of mechanism involving the principles 70 of my invention is connected.

Fig. 2 is a section taken on line 2—2 of Fig. 1.

Fig. 3 is an enlarged detail view of an intermediate connecting shaft illustrating 75 the relation thereof to other elements of the device.

Fig. 4 is a section taken on line 4—4 of Fig. 1.

Fig. 5 is a section taken on line 5—5 of 80 Fig. 3.

As shown in the drawings:

The reference numeral 1, indicates as a whole a washing machine, which has attached thereto a wringer 2, and mounted 85 diagonally across one end of said washing machine is a reversible driving mechanism adapted to drive both the clothes drum within the machine, and the wringer, in either direction, and either simultaneously or independently, as desired.

The driving mechanism consist of a bevel gear casing 3, in which is mounted a gear 4, adapted to be driven from any suitable source of power, such as an electric motor, 95 and having rigidly secured thereto a small bevel pinion 5, adapted to mesh with a bevel gear 6, mounted on a short shaft 7, journaled in said casing 3. The inner end of said shaft 7, is provided with an apertured 100 collar 8, which fits over the end of said shaft and is removably secured thereon by means of a pin 9, engaging in said apertures. As shown in Fig. 3, said collar 8, is also provided with a pair of oppositely disposed 105 longitudinal slots adapted to receive therein a pin 10, substantially at right angles to said pin 9, said pin 10, extending through a

transverse aperture in the end of an intermediate shaft section 11.

A casing 12, is mounted centrally on the end of said machine, and contains therein 5 the reversible driving mechanism for the clothes drum of the washing machine. The clothes drum, although not shown, is rigidly connected to a shaft 13, which is journaled in a bearing 14, forming a portion of the 10 rear wall of said casing, and secured on the inner end of said shaft 13, is a bevel gear 15. An outer cover 16, is provided for said casing 12, and is adapted to be secured thereon by means of bolts or screws 17. Said 15 cover and said casing are each enlarged and extended at points on the periphery thereof to afford split bearing members 18, and 19, respectively.

Journaled in said bearings 18, and 19, is 20 a shaft section 20, which has feathered thereon within said casing 12, a clutch member 21, adapted to interlock with either one of a pair of bevel pinions 22, and 23, respectively, which mesh with said bevel 25 gear 15, and are free to rotate upon said shaft section 20. A lever 24, is pivotally mounted in the upper end of said casing 12, and engages said clutch element 21, for the 30 purpose of shifting the same into its various positions.

Secured on the outer ends of said shaft section 20, are collars 25, similar in construction to the collar 8, already described, and detachably retained upon said shaft 35 section 20, by means of removable pins 26, said collars 25, also bearing against the outer extremities of said journals 18, and 19, respectively, thus maintaining said shaft section 20, properly disposed within said 40 casing 12. A pin 27, is secured in the end of said section 11, already referred to, and engages in the slots in one of said collars 25, similar to the engagement of said pin 10, in said collar 8, and it is to be noted in this 45 particular that said pins 10 and 27, are disposed at right angles to one another in said shaft section 11, so that, together with the slotted collars which receive the same, a universal joint is afforded, which readily 50 takes care of any irregularities in alinement of the mechanism.

A casing 28, is also secured at the upper end of the device to contain therein the reversing mechanism for the wringer, which 55 is similar to that already described. A shaft section 29, is journaled in said casing 28, and feathered thereon is a jaw clutch element 30, adapted to engage either one of bevel pinions 31, and 32, respectively, 60 which are free to rotate on said shaft section 29. Both of said bevel pinions 31, and 32, mesh with a bevel gear 33, which is rigidly secured upon a shaft section 34, journaled at right angles to said 65 shaft section 29. A shaft 35, is directly

connected to the wringer, and is connected to said shaft 34, by means of pins and a collar 36, similar to the collars 10, and 25, already described. Said shafts 20, and 29, are connected to one another by means of an intermediate shaft 37, which is connected to each of said shafts by means of collars 25, and 38, respectively, the pin connections being identical with those already described. 70

Thus it is readily apparent that due to the 75 pin and slot connections existing between the various shaft sections of the mechanism, that substantially a series of universal joints is afforded, thus obviating the necessity of a delicate alinement of the parts in the assembly thereof. Furthermore, for instance, by the withdrawal of said pins 9, and 10, 80 said collar element 8, may be moved over said shaft section 11, thus permitting the same to be withdrawn at its other end from 85 said collar element 25, should it be desired to repair or replace the same.

Likewise the other various elements of the device, by merely removing the pair of pins at any particular collar connection 90 thereon, may be disassociated from one another in an easy and rapid manner without interference with other portions of the device. In order to inclose the elements to 95 protect the same a plurality of slideable tubular elements 39, are provided, of such length as to permit a longitudinal movement thereof at one of the ends for the purpose of uncovering a collar connection to permit removal thereof. 100

I am aware that various details of construction may be varied through a wide range without departing from the principles of this invention. I therefore do not purpose limiting the patent granted otherwise than necessitated by the prior art. 105

I claim as my invention:

1. In a device of the class described a plurality of shaft sections, pins associated therewith, collars having apertures near one 110 end thereof adapted to receive said pins for rigidly and detachably securing said collars on the ends of said sections, said collars having slots in the other end thereof, a plurality of shaft sections, and pins mounted 115 at right angles to each other in the opposite ends thereof adapted to engage in said slots to transmit the drive between said shaft sections.

2. In a device of the class described a 120 plurality of shaft sections, slotted and apertured cylindrical collars removably secured on said sections, a plurality of intermediate shaft sections adapted to transmit the drive between said shaft sections, and pins secured 125 in said intermediate sections, and in said shaft sections adapted to engage in the slots and apertures in said collars, thus affording a flexible connection between said shaft sections. 130

3. In a device of the class described a plurality of shaft sections, bearings for said shaft sections, intermediate shafts adapted to connect said shaft sections, cylindrical 5 collars having apertures and slots therein adapted to properly maintain the shaft sections in the supporting bearings therefor, and pins in said shaft sections and in said intermediate shafts adapted respectively to 10 engage in said apertures and slots in said

collars to afford a flexible driving connection between said shaft sections.

In testimony whereof I have hereunto subscribed my name in the presence of two subscribing witnesses.

HAROLD W. EDEN.
